CLAIM

I claim the ornamental design for a spiral garden, substantially as shown and described.

DESCRIPTION

FIG. 1 is a perspective view of a spiral garden according to my invention.

FIG. 2 is a top plan view of the spiral garden according to my invention; and,

FIG. 3 is a side elevation view of the spiral garden according to my invention.

1 Claim, 3 Drawing Sheets

FIG. 1

FIG. 2

FIG. 3
